PLANOGRAPHIC PRINTING PLATE

George S. Rowell, Cleveland, Ohio, assignor to
Multigraph Company, Wilmington, Del., a cor-
poration of Delaware

Application January 26, 1934, Serial No. 708,401

8 Claims. (Cl. 101—491)

This invention relates to a planographic printing plate having a metallic surface and adapted for carrying an ink-receptive image and an ink-repellent on the non-image areas. The present application is a continuation in part of my co-pending application Serial No. 550,310, filed July 13, 1931. One of the objects is to provide such plate with a surface especially suitable for holding viscous ink repellent such as is used in so-called "dry" lithography.

Another object is to construct the plate so that it shall be sufficiently yielding to readily operate in a planographic manner in direct printing so that, if desired, the plate may be employed either in an offset press or a direct press. Other objects are cheapness of construction; lightness of weight of the completed plate; flexibility to enable it to be readily rolled around the platen of an ordinary typewriting machine to receive an image, or to be drawn taut in the press.

My invention is hereinafter more fully explained in connection with the drawing, and the essential features are summarized in the claims.

In the drawing,

Fig. 1 is an edge view of my complete plate greatly magnified;

Fig. 2 is a perspective of the base member thereof;

Fig. 3 is a diagrammatic elevation of an apparatus for spraying molten metal on the base of Fig. 2, after the manner of the well-known Shoop method.

In the drawing, A represents a sheet of "fabric" which may be paper, felt, a finely woven textile, or other non-metallic material. B represents a coating of minute, rounded, cohering metallic particles adhering to the sheet A. An adhering film of these cohering metallic particles may be readily formed in situ by a spray gun C, as illustrated in Fig. 3, which is supplied by three conduits c', c² and c³ feeding it with oxygen, acetylene and compressed air, or other means to obtain a discharge of compressed gas together with a high heat. c indicates a wire of metal fed to the spray gun and fused and propelled by it, as set out for instance in Patent No. 1,549,843 of Nicolaus Meurer, issued August 18, 1925.

Assuming for instance, that the wire supplied to the gun is zinc, which is the preferred metal, the burning gas will melt the same at the nozzle of the gun and the compressed air will propel it in the form of minute molten particles b which, on contact with the fabric base A, solidify and adhere thereto, and thus form in situ the coating B on the said base.

It is obvious that some particles will fall on and cohere with other particles previously attached to the base A. Such superimposition of particles is not objectionable so long as the "graininess" produced thereby is fairly uniform throughout the area of the plate. As those skilled in the art well understand, the grain of a planographic plate plays an important role in the performance of the plate and it is one of the advantages of the plates of this invention that the conjoined particles constituting the printing surface provide a better type of grain than can be obtained by grinding or sandblasting sheet metal, as is the usual practice.

While the metallized surface of the plates of this invention should be continuous and effect complete coverage of the base material, the thinnest portion of the metallized surface need not be thicker than a single particle constituent thereof. The difference between the thinnest portions of the metallized surface and the thickest portions thereof is determined by the superimposition of particles, as above mentioned, and by the character of the desired "grain."

Complete coverage of the surface of the base material by the metal particles and a substantially uniform "graininess" throughout the area of the plate may be obtained by conventional manipulation of the spray gun, whereby it is caused to traverse the plate by a reciprocating motion while the latter is progressively moved in a direction normal to that of the path of the gun's movement. As apparatus suitable for the purpose is commonly used for metal spray-coating, no further description thereof is deemed necessary here.

Particles obtained by spraying molten metal are rounded and may be sometimes dome shaped as schematically illustrated in Fig. 1, and are thus better adapted for retaining a chemical ink repellent and particularly viscous repellents than the sharp pyramidal surface made by mechanical graining or sand-blasting, as stated. The character of the spray is controlled by the air pressure and temperature developed at the spray gun, and hence, the fineness of the spray may be varied and controlled as desired, and by these means I can vary the size of the individual particles and thus, in conjunction with the mentioned relative and progressive motion of the plate and gun, I can effect complete coverage of the surface of the base and, as stated, produce the kind of graininess best suited for the printing intended.

An advantage of my non-metallic fabric back- 55

ing is that there is a recoverably-yielding layer back of the metallic face, which enables direct printing with many of the advantages of offset printing, and also saves wear on the journals of the rollers by reducing the pressure required.

I am aware that metal foils have been heretofore backed with paper and used as planographic plates; but such prior plates, not only had to be mechanically grained, but the foils had to be

thick enough to stand the graining operation and, in consequence, were devoid of the desirable recoverably-yielding characteristic of the plates of this invention. Thick metal foils, even when mounted on a non-metallic backing, tend to be disadvantageously emboss. It is an advantage of my plate that embossing is substantially avoided.

Because of the very tenuousness of the metallic film, derived from the coherence of the sprayed particles, which constitutes the printing surface of my improved plate, I prefer to employ a backing which is capable of taking the strain, incident to attachment to the form roll and the printing operation, without stretching the metallic facing beyond its elastic limit. Fabric sprayed in a stretched condition is suitable for my purpose, as is also any good grade of heavy rag bond paper. I do not wish to imply a limitation to the mentioned backings, because it will be obvious to those skilled in the art that other backings may be used without departing from the scope of the invention as defined in the appended claims.

I claim:

1. A planographic printing plate comprising a flexible backing, a metallic facing consisting of a

plurality of metallic particles adhering to the backing, and an ink receptive image applied directly to the particles.

2. A planographic printing plate comprising a flexible backing, a flexible metallic facing consisting of a plurality of metallic globules adhering to the backing, and an ink receptive image applied directly to the globules.

3. A planographic printing plate comprising a flexible backing, a metallic facing consisting of a plurality of zinc particles adhering to the backing, and an ink receptive image applied directly to the particles.

4. A planographic printing plate comprising a flexible backing, a flexible metallic facing consisting of a plurality of zinc globules adhering to the backing, and an ink receptive image applied directly to the globules.

5. A planographic printing plate comprising a flexible backing and a metallic facing consisting of a plurality of cohering metallic particles adhering to the backing.

6. A planographic printing plate comprising a flexible backing and a flexible metallic facing consisting of a plurality of cohering metallic globules adhering to the backing.

7. A planographic printing plate comprising a flexible backing and a metallic facing consisting of a plurality of cohering zinc particles adhering to the backing.

8. A planographic printing plate comprising a flexible backing and a flexible metallic facing consisting of a plurality of cohering zinc globules adhering to the backing.

GEORGE S. ROWELL. 35
